CLAIM

The ornamental design for a case, as shown and described.

DESCRIPTION

FIG. 1 is a top front perspective view of a case showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is an exploded top front perspective view of the case of FIG. 1, separating a first case part from a second case part;
FIG. 9 is a front view of the second case part of FIG. 8;
FIG. 10 is a rear view thereof;
FIG. 11 is a left side view thereof;
FIG. 12 is a right side view thereof;
FIG. 13 is a top view thereof;
FIG. 14 is a bottom view thereof;
FIG. 15 is a top view thereof showing the second case part in an environment in which it may be used;
FIG. 16 is a front view of the first case part of FIG. 8;
FIG. 17 is a rear view thereof;
FIG. 18 is a left view thereof;
FIG. 19 is a right side view thereof;
FIG. 20 is a top side view thereof; and,
FIG. 21 is a bottom view thereof.

The broken lines in the Figures show portions of the case or environment that form no part of the claimed design.
